INSULATING COVER FOR A WATER CONDITIONING TANK OR THE LIKE

Jean O. Reinecke, Chicago, Ill., assignor to Culligan, Inc.,
Northbrook, Ill., a corporation of Delaware

Filed June 23, 1959, Ser. No. 56,492

Term of patent 14 years

(Cl. D91—1)

FIG. 1 is a front elevational view of an insulating cover for a water conditioning tank or the like embodying my new design;

FIG. 2 is a side elevation thereof;

FIG. 3 is a top plan view thereof; and

FIG. 4 is a sectional view on the line 4—4 of FIG. 1 to better show the configuration of the open top and the panel.

I claim:

The ornamental design for an insulating cover for a water conditioning tank or the like, substantially as shown.
